UNITED STATES PATENT OFFICE.

FERNANDO G. LANE, OF AUSTIN, TEXAS.

BARREL-COVER.

SPECIFICATION forming part of Letters Patent No. 278,563, dated May 29, 1883.

Application filed April 24, 1883. (No model.)

To all whom it may concern:

Be it known that I, FERNANDO G. LANE, a citizen of the United States, residing at Austin, in the county of Travis and State of Texas, 5 have invented certain new and useful Improvements in Covers for Barrels, of which the following is a specification, reference being had therein to the accompanying drawing.

This invention relates to certain improvements in covers for barrels; and it has for its object to provide improved means whereby the cover can be retained on the edge of the barrel when elevated to expose the contents, so that they can be removed as required, as more 15 fully hereinafter specified. These objects I attain by the means illustrated in the accompanying drawing, in which is represented a vertical sectional view of a barrel, showing my improved cover applied thereto, and showing 20 the cover, in dotted lines, in an elevated position.

The letter A indicates a barrel of ordinary construction, and B a cover having at its periphery a downward-extending flange, B'. The 25 said cover is adapted to set over the upper edge of the barrel, the flange extending around the said upper edge, so as to make a secure joint. At the center is secured a knob, C, by means of a screw-bolt or other fastening device.

30 The inner edges of this knob set some distance

away from the inner face of the cover, so as to leave a space, D, between the two.

The operation of my invention will be understood from the above description. When the barrel is covered the top sets horizontally 35 on the upper edges of the same. When uncovered the top is thrown back until it rests on the piece shown in dotted lines, when the knob catches the inner edge of the barrel and holds it up in an elevated position, so as to 40 leave the mouth open for ingress to the inside.

It will be seen by my invention that the top or cover of the barrel may be readily placed out of the way over the mouth of the same, and still be held conveniently in position to be 45 replaced.

Having thus described my invention, what I claim, and desire to secure by Letters Patent, is—

A barrel-top consisting of a flanged disk 50 having a central knob on its under side, adapted to catch the upper edge of the barrel and hold the top in an elevated position, substantially as and for the purpose specified.

In testimony whereof I affix my signature in 55 presence of two witnesses.

FERNANDO GUSTAVOUS LANE.
